UNITED STATES PATENT OFFICE.

WILLIAM V. ORR, OF CLEVELAND, OHIO.

SUCTION CLEANING DEVICE.

1,210,525.

Specification of Letters Patent. Patented Jan. 2, 1917.

Application filed September 27, 1915. Serial No. 52,786.

To all whom it may concern:

Be it known that I, WILLIAM V. ORR, a citizen of the United States, residing at Cleveland, in the county of Cuyahoga and 5 State of Ohio, have invented a certain new and useful Improvement in Suction Cleaning Devices, of which the following is a full, clear, and exact description, reference being had to the accompanying drawings.

10 This invention relates to suction cleaners and has for its object the provision of a device of this nature which shall efficiently take up and collect not only the dust and grit which adheres to floors and floor coverings, but also pieces of thread, lint, dressmakers' scraps, matches, slips of paper and the like.

I am aware that rotating brushes, mechanical beaters, and such appliances have 20 been employed for agitating such refuse and lifting it into the air stream, but my object is to dispense with such complicated and expensive devices, and so to design the nozzle that such refuse will be picked up by a 25 properly directed air stream and elevated into the cleaner in a simple and reliable manner.

While I conceive that certain features of 30 my invention might be of value in connection with a rotating brush or other movable agitating device, I have illustrated and prefer to use with my machine a form of fixed brush rigidly secured in the nozzle and serving not only to displace the carpet substance, but also to break up the entering air 35 stream into a plurality of independent separate jets.

The essence of my invention consists in this, that the air entering under one lip of 40 my improved nozzle is caused to blow against the opposite inclined lip in such fashion as to elevate thereon the foreign matters lying on the carpet, said wall being of a uniform moderate inclination whereby 45 the air stream may elevate such refuse therewithout obstruction and so deliver it to the suction device. In the performance of my said invention I preferably employ within the limits of the inlet mouth, 50 a depending wall or partition located between the lips thereof but terminating a slight distance above the plane of said lips, said wall being spaced from one of said lips to define an inlet slit and from the other 55 lip to define a brush receiving cavity; and in the preferred form of my invention the

lip adjacent to said cavity is disposed at a higher level than the other lip so that air may enter beneath said first lip and pass beneath said wall and finally be discharged 60 toward the face of said other lip.

In the drawings accompanying and forming a part of this application I have illustrated one embodiment of my invention and in these drawings, Figure 1 represents a 65 perspective view of a cleaner casing embodying my invention; Fig. 2 is a vertical-longitudinal section through the nozzle, the fan casing and dust bag being shown in elevation; Fig. 3 is a bottom plan view of 70 the said nozzle, and Fig. 4 is a perspective view of the nozzle showing the shape of the air passage at different points.

Describing the parts by reference characters 1 represents the fan casing of a portable suction cleaner, 2 the motor casing axially secured thereto, and 3 the collecting nozzle which projects obliquely forwardly from the opposite end of the fan casing, said nozzle increasing in width as it departs 80 from said fan casing and being formed at its extremity with a pair of spaced parallel lips 4, 5 defining an elongated inlet mouth. Said nozzle is supported by means of suitable rollers 6-6, and the rearward part of 85 the machine by means of a suitable roller 7, the former rollers being preferably vertically adjustable as by being mounted on the crank-shaped rock-shaft 8 which may be adjusted to any desired height by moving 90 the lever 9. The casing is moved about as occasion demands by means of the usual handle 10, and the dust and dirt collected is received in a suitable bag 11 secured to an outlet neck 12 projecting from the periphery 95 of the fan chamber. In this type of cleaner the fan 13 is supported with its axis horizontal as shown in Fig. 4.

While I have chosen here for purposes of illustration a cleaner of the horizontal type 100 it is not with the idea of limiting myself thereto.

The interior of the nozzle 3 is formed with one or more passageways establishing communication between the inlet mouth and the 105 opening 15 in the end wall of the fan chamber. The lower wall of said nozzle consists of a substantially flat plate 16 whose external lines define a truncated triangle of which the lip 5 forms the base. The upper wall of 110 the nozzle consists of a similarly shaped plate 17, whose base part is caused to pro-

ject for a distance substantially horizontally in front of and above the lip 5 as shown at 18 before terminating in the depending skirt 19 which ends in the lip 4. This horizontal ledge 18 defines a chamber extending from end to end of the suction mouth, and in this chamber between the two lips, I locate a wall 20, the same being here shown as a kind of hollow sheet metal bead having a flat top spaced from the plane of the lips 4, 5 and having at one side the inclined portion 21 projecting inside the wall 17 so as practically to form a continuation thereof and having the other side bent abruptly as shown at 22 and spaced from the skirt 19 to form a brush receiving cavity. The space between the lip 5 and the incline 21 I have termed the suction slot, the same being in the form of a narrow passage, which extends from end to end of the suction mouth of the nozzle. From this slot to the opening 15 the walls 16 and 17 diverge, so as largely to compensate for their taper laterally. Also I have shown said walls as connected by a transverse wall 24 forming an oval symmetrical deflector extending along the longitudinal axis of the nozzle from a point adjacent the slot to a point adjacent the opening 15. In the present embodiment this wall 24 defines an open recess formed in the bottom wall 16, its size and shape being so chosen as to prevent all obstructions and sharp points and to maintain the cross-sectional area of the nozzle passageway substantially uniform throughout its length.

By referring to Fig. 4 wherein I have shown the cross sectional shape of the passageways at various points it will be seen that at the plane *a* each slot is long and narrow, becoming deeper and more rounded at the planes *b* and *c* until as it approaches closely to the fan it assumes a distinct triangular shape as shown at *d*. The bottom of each passageway is disposed on a straight line as shown in Fig. 2 and the axes of the passages are indicated by the lines *e*, *e* in Fig. 4, which lines preferably pass through the center of the fan. This arrangement of the passageways collects the refuse into small compass inside a compact stream of air, thereby rendering the cleaner unusually efficient.

The lip 4 being elevated slightly above the lip 5 the result is to set up a shallow horizontal sheet of air moving along the top of the carpet and directed toward the lip 5 which is inclined upwardly at a uniform angle as heretofore stated. The adjustability of the supporting wheels permits the edge of the lip 5 to be set at a level just beneath the top of the carpet nap so that debris lying on the carpet will be caught upon this lip as upon a dust pan, after which the air stream will elevate it into the fan chamber.

In Figs. 2 and 3 I have illustrated a brush

secured in the nozzle and comprising a solid base member 25 adapted to fit snugly in the cavity prepared for it and carrying on its exposed face a plurality of spaced tufts 26 of bristles whose length is preferably such as to cause them to project as low as, or lower than, the lip 5.

While I have described my invention in detail I do not propose to be limited to such details except as the same may be definitely recited in the claims or may be rendered necessary by the prior state of the art.

Having thus described my invention, what I claim is:—

1. In a suction cleaner, a collecting nozzle having converging upper and lower walls, and diverging side walls, all terminating in an elongated mouth, and a symmetrical deflector extending between the upper and lower walls, behind said mouth, said deflector being shaped to form two passages in said nozzle, each passage being of substantially the same cross-sectional area throughout its length.

2. In a suction cleaner, a collecting nozzle comprising upper and lower converging walls terminating in a pair of spaced parallel lips defining an inlet mouth, one of said lips being lower than the other lip and having its upper surface inclined away from said other lip, in combination with a plate extending rearwardly from the upper lip, above said inlet mouth, said plate having a rearwardly and upwardly inclined portion projecting within said upper wall and forming a continuation thereof.

3. In a suction cleaner, a collecting nozzle terminating in a pair of spaced parallel lips defining an inlet and a wall located between said lips and parallel thereto, said wall being spaced from one lip to form a suction slot and from the other lip to form a brush receiving cavity, a portion of said wall being substantially parallel to and spaced inwardly from the plane of the mouth defined by the edges of said lips.

4. In a suction cleaner, a collecting nozzle terminating in upper and lower lips defining an inlet mouth, a dividing wall projecting from the upper lip over said mouth and spaced from the lower lip to form a suction slot and from the upper lip to define a brush chamber, said wall terminating at a point in the nozzle behind said inlet mouth, and a brush secured in said brush chamber and projecting downwardly beyond said wall, at the edge of said mouth.

5. In a suction cleaner, a nozzle having upper and lower walls terminating at one end in a narrow suction slot, and at the opposite end in an outlet opening, said walls diverging from each other as they recede from said slot and the sides of said nozzle transverse to said slot converging toward each other as they recede from said slot, and

a hollow deflector located between said slot and the outlet from said nozzle and symmetrically about the longitudinal axis of said nozzle, said deflector having an angle presented toward said slot at substantially the middle point thereof and having at its opposite part an angle presented toward said outlet, the cross sectional area of the air passage within said nozzle remaining substantially constant from point to point, the axis of said air passage lying in a straight line which intersects the center of the outlet.

6. In a suction cleaner, a fan chamber hav-

ing a central inlet opening and a pair of spaced passageways leading from said opening, said passageways merging together at a distance from said opening to form a common suction slot, the width of each passageway increasing and its depth decreasing as it recedes from said inlet opening while keeping its cross sectional area substantially uniform.

In testimony whereof, I hereunto affix my signature.

WILLIAM V. ORR.
